Attorney.*

UNITED STATES PATENT OFFICE.

ED WHITAKER, OF WATERLOO, IOWA, ASSIGNOR, BY DIRECT AND MESNE ASSIGNMENTS, OF ONE-THIRD TO IRETA L. ESCHER, OF CHICAGO, ILLINOIS.

COMBINATION HEADLIGHT REFLECTOR.

Application filed February 5, 1924. Serial No. 690,747.

To all whom it may concern:

Be it known that I, ED WHITAKER, a citizen of the United States of America, and a resident of Waterloo, Black Hawk County, ⁵ Iowa, have invented certain new and useful Improvements in Combination Headlight Reflectors, of which the following is a specification.

My invention relates to improvements in ¹⁰ combination headlight reflectors, and the object of my improvement is to supply a lamp of this type with such a combination of reflecting devices about a source of illumination, that the light from said source shall ¹⁵ be all substantially employed, and directed to illuminate a desired limited area.

This object I have accomplished by the means which are hereinafter described and claimed, and which are illustrated by the ²⁰ annexed drawings, it being understood that changes in the precise embodiment of invention herein disclosed can be made within the scope of what is claimed without departing from the spirit of the invention.

²⁵ In said drawings, Fig. 1 is a vertical medial longitudinal section of my improved device, and Fig. 2 is a front elevation thereof.

It is desirable and necessary that head- ³⁰ lights of vehicles which include a relatively powerful source of illumination should also include means for segregating the directed light toward certain limited areas in advance to avoid inconveniencing the drivers ³⁵ of vehicles approaching from an opposite direction, and it is also desirable that substantially all of the light rays emitted by said source should be employed for that purpose without having a certain proportion ⁴⁰ lost because of being radiated into space without the desired limited area being properly illuminated.

My device is therefore contrived to secure ⁴⁵ both these desired objects, and of course both the elements of the lamp and the kind of source of illumination may be varied at will to effect these results.

In the drawings is shown in exemplification one kind of lamp comprising a lamp- ⁵⁰ shell 2 within which is mounted a parabolic reflector 1, their interspace receiving the conducting wires of an electric-lamp bulb

⁵⁵ mounted in a socket 8, the wires also being connected to another socket of the usual type set in an opening in said shell 2 and having engaging-means for a coupling to other conductors.

The numeral 6 denotes a curvate hood whose inner face is a reflector opposed to the reflector 1 and detachably mounted over ⁶⁰ the upper forward part of the latter slopingly.

Instead of mounting an electric lamp at or near the focal point of the reflector 1, I have mounted it adjacent the upper part of ⁶⁵ the inner reflecting face of the hood 6, an opening being provided in said hood to receive the socket 8 therethrough, and I have also provided a removable housing member ⁷⁰ 7 about said socket 8 secured to said lamp-shell and to said hood.

The numeral 5 denotes a flat segmental covering plate for the lower part of the reflector 1, having its inner face provided ⁷⁵ with a reflecting surface opposed to the reflector 1 and secured detachably to the lamp-shell below the hood 6, this plate 5 serving as a lower reflecting screen, and the interspace of the screens 5 and 6 being filled by a transparent plate 10 mounted between ⁸⁰ 80 clamping elements 11.

When the parabolic or other kind of concave reflector 1 has an opening as in ordinary lamps to receive a bulb-socket, and it is desired to apply the screens 5 and 6 or ⁸⁵ either of them to the reflector as shown, the opening 3 may have a stem secured therein provided with a domical boss 4 having a reflecting surface, to prevent any interruption of the reflecting face of the reflector.

As so constructed and arranged, with the lamp 9 positioned above and forward of the focal point of the reflector 1 and near the hood 6, light rays from the lamp are reflected from the hood toward the reflector 1, and light rays which are directed from the lamp upon said reflector are in part reflected toward the reflecting surface of the lower plate 5, whereby the lamp rays are approximately wholly directed through the window-plate 10 and by the restriction of the parts ⁹⁵ 5 and 6 are directed to illuminate a desired area ahead as indicated by the scope between the horizontal and vertical arrows in Fig. 1. ¹⁰⁰

The light is thus dimmed for an approaching vehicle, and concentrated on the road properly.

Having described my invention, what I claim as new, and desire to secure by Letters Patent, is:

A device of the character described, comprising a concave reflector, a curvate hood positioned across the upper front part of the reflector and having an inner reflecting face, a source of illumination adjacent the said reflecting face above the focal point of the

concave reflector, and a flat reflector screen positioned across the lower front part of said concave reflector and with a horizontal upper edge spaced vertically from the lower edge of said upper hood, the hood and screen cooperating in directing light emitted between them within certain vertical limits and emitting light laterally between the hood and screen. 15 20

Signed at Waterloo, Iowa, this 10th day of Jan., 1924.

ED WHITAKER.
